TOY AUTOMOBILE

Melvin S. Lower, Wadsworth, Ohio, assignor to
The Sun Rubber Company, Barberton, Ohio, a
corporation of Ohio

Application November 2, 1934, Serial No. 751,136

3 Claims. (Cl. 46—201)

The present invention relates to improvements in toy automobiles preferably made of hard rubber and molded to simulate the designs of real automobiles, and has for its primary object to produce such a toy which is simple and inexpensive to manufacture and of such ornamental characteristics as to be appealing particularly to children.

Another object of the present invention is the provision of an improved wheel assembly and the manner in which it is mounted upon and carried by the body of the toy automobile.

A still further object of the invention is to provide a covering for the ordinarily exposed elements, such as the ends of the axles or wheel hubs, which might otherwise damage articles of furniture or cause injury to the children.

With the objects above indicated and other objects hereinafter explained in view, my invention consists in the construction and combination of elements hereinafter described and claimed.

Referring to the drawing,

Figure 1 is a side elevational view of a toy automobile embodying the present invention;

Figure 2 is a bottom plan view of the same showing the improved manner in which the wheel assemblies are mounted and supported;

Figure 3 is a transverse sectional view taken on line 3—3 of Figure 1;

Figure 4 is a longitudinal sectional view taken on line 4—4 of Figure 3;

Figure 5 is a transverse sectional view similar to Figure 3, but showing a modified form of wheel assembly; and

Figure 6 is a transverse sectional view similar to Figure 3, but showing a further modified form of wheel assembly.

In the drawing, a toy automobile is illustrated wherein a body 10 is formed to simulate the design of the present type of pleasure vehicle having a hood 11, fenders 12, running boards 13, doors 14, etc., all made of rubber and preferably by molding to produce an integral structure. The body 10 may be made from rubber of various colors and the radiator, head lights, louvers, door handles and other similar parts may be painted with aluminum or other contrasting color to produce a pleasing appearance which will appeal particularly to children for whom the toy automobile is intended.

To lighten the body 10 and also to conserve on the quantity of rubber used, a recess 15 is provided adjacent the mid-section thereof and

extends upwardly from the under side to adjacent the top for any desired distance.

Pairs of wheel recesses 16 and 17 are also formed in the under side of the body 10 as shown in Figure 2, the recesses 16 being located at the front end thereof while the recesses 17 are located at the rear end. The pairs of recesses 16 and 17 are preferably aligned longitudinally while the recesses of each pair are suitably spaced apart and aligned transversely. A transverse opening 18 is formed in the under side of the body 10 and extends between the recesses 16. A slot 19 of relatively small width is also formed in the under side of the body and provides an entrance to the opening 18 for a purpose to be later described. A similar transverse opening 20 is formed between the recesses 17 and likewise has an entrant slot 21 for a similar purpose.

A front wheel and axle assembly 22 and rear wheel and axle assembly 23 are provided and inasmuch as these constructions are identical it will suffice to describe the front one. A pair of wheels 24 preferably of rubber are mounted upon an axle 25 for free rotative movement thereon and the opposite ends of the axles may be upset to provide heads 26 to prevent disengagement of the wheels. These wheel assemblies may be made up separately and by reason of the body construction are easily later mounted thereon as will be hereinafter described.

After the body 10 has been molded according to any desirable and well-known method, the wheel assemblies may be mounted thereon by separating the wheels and forcing the axle through the entrant slot 18 into the opening 18. The slot 18 being of relatively small width in comparison with the size of the axle 25 prevents accidental disengagement between the axle and body and the resiliency of the rubber material of the body tends to retain the axle 25 securely within the opening 18. To assist in inserting the axle 25 through the slot 19, the adjacent end of the body 10 may be distended due to the flexibility of the rubber as shown by dotted lines in Figure 4 until the slot 19 has been extended sufficiently to permit the axle to readily pass therethrough into the opening 18, after which the end may be released and the resiliency of the rubber will return the same to its normal position and thereby secure the axle in proper position.

There are numerous ways in which these wheel assemblies may be constructed, several modifications of which are shown in the following figures. In Figure 5 a commercial type of rivet is used for the axle 25 which is provided with a head

27 at one end and a split opposite end, the free ends of which may be upset at 28 to retain hubs 29 upon the shaft 25. These hubs have circumferential grooves 30 to receive an inner circumferential flange 31 formed on a rubber tire 32 and from which the latter may be easily removed. The outer side of the tire 32 is closed at 33 to provide a suitable covering for otherwise exposed ends of the shaft. This prevents damage to articles of furniture and injury to children.

10 A different assembly is shown in Figure 6 wherein the axle 25 is formed from a commercial type of rivet of slightly different form having a head 34 at one end and the opposite end 15 split, the free ends of which are upset at 35 to prevent disengagement of the rubber tires 36. In this case the rubber tires are mounted directly upon the axle and the exposed ends of the latter are covered by forming skirts 37 integral with 20 the fenders and extending across the ends of the shaft. This arrangement affords the same protection as that shown in Figure 5.

25 While I have described the preferred embodiments of the invention, it should be understood that I am not to be limited thereto inasmuch as changes and modifications may be resorted to without departing from the spirit of the invention as defined in the appended claims.

What is claimed is:

30 1. A vehicle body of resilient material having in the bottom portion thereof a transversely ex-

tending opening and communicating entrant slot receiving a wheel and axle assembly, said body being of such resiliency and shape that its flexure causes a divergence of the outward edges of the slot walls thereby temporarily enlarging its entrance to permit the ready insertion of said axle into said opening.

2. A vehicle body of resilient material having in the bottom portion thereof a transversely extending opening and communicating entrant slot 10 receiving a wheel and axle assembly, said body being of such resiliency and shape that its flexure causes a divergence of the outward edges of the slot walls thereby temporarily enlarging its entrance to permit the ready insertion of said axle 15 into said opening, said body returning to its normal position upon being relieved of its flexure whereby said axle is secured in said opening against relative rotation.

3. A vehicle body of resilient material having 20 in the bottom portion thereof a transversely extending opening and communicating entrant slot receiving a wheel and axle assembly comprising a pair of wheels rotatably mounted on a shaft the opposite ends of which have integral enlargements, said body being of such resiliency and shape that its flexure causes a divergence of the outward edges of the slot walls thereby temporarily enlarging its entrance to permit the ready 25 insertion of said shaft into said opening.
